CABINET FOR A MAGNETIC TAPE TRANSPORT

Robert W. Borschlegel, Millbrae, Calif., assignor to
Ampex Corporation, Redwood City, Calif., a corpora-
tion of California

Filed Apr. 2, 1964, Ser. No. 79,318

Term of patent 14 years

(Cl. D26—5)

FIGURE 1 is a front and right side perspective view of a cabinet for a magnetic tape transport, showing my new design; and

FIGURE 2 is a rear and left side perspective view.

I claim:

The ornamental design for a cabinet for a magnetic tape transport, substantially as shown.
